DESCRIPTION

FIG. 1 is a right side elevational view of a telehandler having the ornamental features of the present invention.

FIG. 2 is a left side elevational view of the telehandler shown in FIG. 1.

FIG. 3 is a rear view of the telehandler shown in FIG. 1.

FIG. 4 is a front view of the telehandler shown in FIG. 1; and,

FIG. 5 is a top view of the telehandler shown in FIG. 1.

The tires, wheels and axle assemblies are shown in broken lines, where ever they appear in FIGS. 1-5 of the drawings, are for illustrative purpose only and form no part of the design.
